FIG. 4.

UNITED STATES PATENT OFFICE

2,600,656

SUPPORT FOR OVEN BURNER ASSEMBLIES

Kenneth S. Jenson and Willis N. Nelson, Wisconsin Rapids, Wis., assignors to Prentiss Wabers Products Company, Wisconsin Rapids, Wis., a corporation of Wisconsin

Application May 12, 1950, Serial No. 161,656

8 Claims. (Cl. 126—39)

1

This invention relates to an oven burner assembly, and particularly to an improved support therefor, such as may be used to advantage in a gas cooking range for the home or elsewhere.

In the construction and operation of a gas cooking range it is important to simplify and expedite the assembly of the parts, and also to facilitate their disassembly whenever occasion therefor arises. To accomplish these ends is a primary object of this invention. For this purpose we utilize certain parts which may be set in place with proper manipulations, and without the use of any tools or fastening elements. A pair of rods extending crosswise of the oven near its base constitute the support for the oven burner assembly and the construction and mounting of these rods is an important feature of this invention.

Other objects and advantages will also appear hereinafter from the detailed description of the accompanying drawing wherein is illustrated a suggestive embodiment of this invention in the manner following:

Figure 1 is a fragmentary front elevation of a gas cooking range with certain parts thereof broken away to exhibit in elevation the front rod support for the oven burner assembly a portion of which appears in section;

Fig. 2 is a vertical section, taken on line 2—2 of Fig. 1;

Fig. 3 is an elevational detail of one of the supporting rods together with the wall supports therefor, the latter being shown in section; and

Fig. 4 which is a view similar to Fig. 2, although mostly in elevation, shows the units of the oven burner assembly in slightly separated relation.

In the illustrated stove there is an oven compartment having spaced side walls 10 and 11 between which is positioned an oven burner assembly comprising a burner A, a burner baffle B, and an oven bottom C. This assembly is supported upon a pair of crosswise rods D extended between the side walls 10 and 11. These rods are disposed at a common level, one toward the front and the other toward the rear of the compartment. Since these rods are alike, a detailed description of but one will be given.

Each rod, formed of wire or the like, is formed with a drop center portion 15 which extends for the major portion of the length of the rod to join with its opposite end portions through inclined connecting sections 16. Normally the rod is rotatively disposed as shown in Fig. 1. The rod is also provided with a short center downset at 17, and its two ends 18 are inclined angularly up-

2

wardly, as shown. The walls 10 and 11 are each provided with a hole 20, one opposite the other, for receiving one end of each rod, and each wall is crimped outwardly at a just above its hole and inwardly at b just below its hole (see Fig. 3), the two crimps being substantially parallel to provide in effect an axis for the hole that is inclined downwardly and outwardly.

In assembling each rod into its operative position, the rod is first turned through 180°, as shown in Fig. 3, so that the axis of one angled end 18 is aligned with that of the hole 20 in the wall 10 wherein it is to be received; the angled end of the rod is then advanced into and through the hole, and the rod is then manipulated properly to perform similarly the operation of inserting its opposite angled end in the hole 20 in the other wall 11. When done, the rod is allowed to swing around by gravity so that its downset central portion 17 will be suspended downwardly and its angled ends 18 inclined upwardly and transversely of the axes of the two holes 20 (see Fig. 1). Each rod, when so positioned, is manifestly prevented from endwise movement and so is effectively locked in place; when turned around through 180° again, counter to the gravity force acting on its drop center, the rod is free to be successively disengaged at its two ends from the supporting holes of the walls 10 and 11.

The two rods D provide a support from which may be suspended the burner A which, as here shown, comprises a hollow casting having at its front end a lateral opening 25 in connection with a manifold 26 through which air is drawn into the burner to support combustion of the fuel. A plurality of burner openings 27 are provided along opposite sides of the burner where combustion takes place, the flames then playing outwardly in the usual way.

At the front end of the burner casting is an upwardly extended arm 30 terminating in a downwardly facing hook 31 which is arranged to engage the central downset portion 17 of the forward rod D. A similar arm 32 is extended upwardly and rearwardly from the proximate end of the burner to terminate in a downwardly facing hook 33 for engaging with the central downset portion 17 of the rod D lying to the rear. It will be noted that the burner, when so supported, is rested loosely on the central downset portions of the two rods and that the arms 30 and 32 are of substantial width so that each will engage its supporting rod for substantially the full length of its central downset portion 17. As a result, the burner is prevented from shifting endwise

along either rod, and so is maintained fixedly in a position centrally thereof, although readily disengageable therefrom.

The baffle B is in the form of a plate which by preference is provided with a depending rib 35 extending from front to rear in its medial region to provide reinforcement therefor. The side edge portions 36 of the baffle plate may also be angled upwardly (see Fig. 1) for a similar purpose. These angled edge portions substantially engage with the rods at the junctures of their connecting sections 16 with their drop center portions 15 so as to confine the baffle plate against shifting movement endwise of the rods. To locate the baffle plate properly and prevent longitudinal shifting thereof, we have struck downwardly therefrom a pair of ears 37 near the front and a similar pair of ears 38 near the rear, these two pairs of ears lying just forwardly and rearwardly of the two rods D when assembled therewith. The baffle plate is arranged to rest upon the drop center portion 15 of each supporting rod and be confined thereupon against lateral or longitudinal shifting movement. In this position the baffle plate is elevated above the burner A a distance sufficient for adequate spread of the flames issuing from the jet openings 27 so as to distribute the heat over a wide area of the baffle plate.

The oven bottom C is also in the form of a metal plate having depending marginal flanges 40 which at the front extends outwardly and downwardly for an enhanced distance in the form of an apron 41. This apron overlies the proximate edge of the baffle plate B and also the forward supporting rod D so that their presence is effectively concealed. The lower edges of the depending marginal flanges 40 rest on the two rods D (see Fig. 1) at four points to the outside of their connecting sections 16, and thereby support the plate C in elevated position above the baffle plate B. This plate constitutes the bottom for the oven which is heated by the flames issuing from the burner A, and which is desirably inclined downwardly very slightly to a low point near its center. Heat transferred through and past the baffle plate is effectively distributed to the under side of the oven bottom plate C which may be fixedly secured in place by fastening means (not shown) in engagement with any convenient part of the range structure.

From the preceding description, it will be evident that whenever any adjustment or replacement of the burner or parts associated therewith is required, the operation of doing so is very simple indeed. It involves merely removal of the oven bottom, lifting of the baffle plate from its supported position upon the rods and, if necessary, lifting of the burner from the supporting rods preliminary to its removal from the oven compartment. The rods may also be taken out, if it be necessary, by a reversal of the simple operation already described. When assembly has been completed, as indicated in Figs. 1 and 2 of drawing, the parts will remain fixedly in their proper positions due, among other things, to the drop center portions 15 of the supporting rods which support the baffle plate B and which are provided with central downset portions 17 from which the burners are suspended.

We claim:

1. In a gas cooking range having an oven compartment, a pair of burner assembly supporting rods extended crosswise of the compartment near its base, one toward the forward end and the other toward the rear, the compartment includ-

ing side walls each having a pair of holes for the end portions of the two rods, the walls above and below each hole immediately adjacent thereto being crimped outwardly and inwardly respectively to provide, in effect, an opening which is extended downwardly and outwardly from the wall, each rod having its opposite end portions bent into substantial parallelism with the axis of one of the holes when the rod is swung around to assembling position, the bent portion at one end of the rod being adapted for free insertion through said hole and when shifted axially therewithin being adapted to be so positioned as to permit insertion of the bent portion at its opposite end within the hole proximate thereto by a like manipulation, the rod when rotated through 180° from its last mentioned position presenting its bent end portions transversely of the axes of the holes whereby to be confined by the wall portions adjacent thereto from endwise movement therewithin.

2. In a gas cooking range having an oven compartment, a pair of burner assembly supporting rods extended crosswise of the compartment near its base, one toward the forward end and the other toward the rear end, the compartment including side walls each having a pair of holes for the end portions of the two rods, the walls above and below each hole immediately adjacent thereto being crimped outwardly and inwardly respectively to provide, in effect, an opening which is extended downwardly and outwardly from the wall, each rod being formed with a drop center and having its opposite end portions bent in a direction oppositely of its drop center and in substantial parallelism with the axes of the two opposite holes when the rod is swung around to a position in which the drop center is uppermost, the bent portion at one end of the rod being adapted to be aligned with the axis of one hole and free for insertion therethrough and when shifted axially therewithin being adapted to be so positioned as to permit insertion of the bent portion at its opposite end within the hole proximate thereto by a like manipulation, the rod when rotated through 180° from its last mentioned position presenting its bent end portions transversely of the axes of the holes whereby to be confined by the wall portions adjacent thereto from endwise movement therewithin, and the drop center portion of the rod being normally suspended in response to gravity whereby to maintain the bent end portions thereof in transverse relation to the axes of the said holes.

3. In a gas cooking range having an oven compartment, a pair of burner assembly supporting rods extended crosswise of the compartment near its base, one toward the forward end and the other toward the rear, the compartment including side walls each having a pair of holes for the end portions of the two rods, each rod being provided with a drop center portion and having its end portions arranged for insertion through opposite holes in the side walls of the compartment whereby to derive support therefrom, a burner positioned within the compartment and extended longitudinally thereof and having at its opposite ends raised means for engaging the drop center portions of the two rods whereby to suspend the burner therefrom at a level therebelow, and a baffle plate supported by the two rods above the drop center portions thereof and positioned over the burner in spaced relation thereto and having means in engagement with the rods for preventing shifting movement thereupon.

4. In a gas cooking range having an oven compartment, a pair of burner assembly supporting rods extended crosswise of the compartment near its base, one toward the forward end and the other toward the rear, the compartment having side walls each formed with a pair of holes for receiving opposite end portions of the rods for support thereof, each rod having a drop center portion for the major portion of its length, a burner extended between the two rods and provided at opposite ends with raised means for engaging the drop center portions thereof whereby to suspend the burner therefrom at a level therebelow, and a baffle plate extended between the two rods and supported thereby above the burner in spaced relation thereto and having means in engagement with the rods for preventing shifting movement thereupon.

5. In a gas cooking range having an oven compartment, a pair of burner supporting rods extended crosswise of the compartment near its base, one toward the forward end and the other toward the rear, the compartment having side walls each formed with a pair of holes for receiving opposite end portions of the rods for support thereof, each rod having a drop center portion extended for the major portion of its length and in its center being further downset for a short distance, a burner extended between the rods and provided with raised means engageable with the downset central portions of the two rods whereby to suspend the burner therefrom at a level therebelow, and a baffle plate supported upon the drop center portions of the two rods in spaced relation to the burner therebelow and having means engaging with the rods for preventing shifting movement thereupon.

6. In a gas cooking range having an oven compartment, a pair of burner assembly supporting rods extended crosswise of the compartment near its base, one toward the forward end and the other toward the rear, the compartment having side walls each formed with a pair of holes, each rod being provided with a drop center portion and having its end portions arranged for insertion through opposite holes in the side walls of the compartment whereby to derive support therefrom, a burner positioned within the compartment and extended longitudinally thereof and having raised means in suspending engagement with the two rods whereby the burner is supported therebelow, a baffle plate supported by the two rods within the confines of their drop centers in spaced relation to the burner therebelow, and an oven bottom positioned within the compartment in spaced relation to the baffle plate therebelow and in supporting engagement with the two rods at points outside their drop centers.

7. In a gas cooking range having an oven

compartment, a pair of burner assembly supporting rods extended crosswise of the compartment near its base, one toward the forward end and the other toward the rear, the compartment having side walls each formed with a pair of holes for receiving opposite end portions of the rods for support thereof, each rod having a drop center portion for the major part of its length, a burner extended between the two rods in suspending engagement with the drop center portions thereof, a baffle plate extended between the two rods above the burner in spaced relation thereto and having means in supporting engagement with the drop center portions thereof, and an oven bottom extended between the two rods above the baffle plate having depending marginal flanges in supporting engagement with the two rods at points outside of their drop center portions whereby to be supported thereby in elevated position above the baffle plate and in spaced relation thereto.

8. In a gas cooking range having an oven compartment, a pair of burner assembly supporting rods extended crosswise of the compartment near its base, one toward the forward end and the other toward the rear, the compartment having side walls each formed with a pair of holes for receiving opposite end portions of the rods for support thereof, each rod having a drop center portion extended for the major portion of its length and in its center being further downset for a short distance, a burner extended between the rods in suspending engagement with the downset center portions thereof, a baffle plate extended between the two rods above the burner in spaced relation thereto and having means in supporting engagement with the drop center portions of the rods, and an oven bottom extended between the two rods above the baffle plate in spaced relation thereto and having means depending from its margins to engage with the rods at points outside of the drop center portions thereof whereby to be supported in elevated position above the baffle plate.
